(57) **CLAIM**

We claim the ornamental design for a water container for humidifier capable of being controlled with wireless communication, as shown and described.

DESCRIPTION

FIG. 1 is perspective view of a water container for humidifier capable of being controlled with wireless communication, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings show portions of the water container for humidifier capable of being controlled with wireless communication which form no part of the claimed design.
